CLAIM

The ornamental design for a connector for air-breathing apparatus, as shown and described.

DESCRIPTION

FIG. 1 is a partial perspective of one side, top and front of a connector for air-breathing apparatus showing our new design, with the pressure regulator being shown in broken lines for illustrative operative understanding; FIG. 2 is a perspective view of the other side, bottom and back of the apparatus shown in FIG. 1.

FIG. 1

FIG. 2
